UNITED STATES PATENT OFFICE.

GUSTAV SEGSCHNEIDER, OF YONKERS, NEW YORK.

HAT-BRIM-CURLING MACHINE.

1,134,353.

Specification of Letters Patent.

Patented Apr. 6, 1915.

Application filed January 17, 1914. Serial No. 812,844.

To all whom it may concern:

Be it known that I, GUSTAV SEGSCHNEIDER, a citizen of the United States, residing in Yonkers, Westchester county, New York, 5 have invented certain new and useful Improvements in Hat-Brim-Curling Machines, of which the following is a specification.

This invention relates to hat-brim curling machines employing a curling-shoe and a 10 curling-hammer co-operating therewith to curl the brim between the hammer and the shoe, such for example as the machine shown in my prior Patent No. 779,242 of January 3d, 1905.

15 The objects of the present invention are to provide automatic means for dampening the brim; also to improve the action of the hammer; and to render the feeding-devices more reliable in operation and more convenient of adjustment than hitherto. The 20 first of these objects is accomplished by arranging a dampening-belt adjacent the path of the brim so that the belt contacts with and properly wets the brim before its entrance between the shoe and hammer. The 25 action of the hammer is improved by mounting the same on a spring-metal arm having proper flexibility to permit the required movement of the hammer hitherto obtained by pivoting the latter, whereby the play inseparable from worn pivoted parts is eliminated. The actuating mechanism for the 30 feed-roller is rendered certain in its operation, and convenient of adjustment, and an 35 improved means of adjusting the feeding-finger is provided.

In the accompanying drawings, Figure 1 40 is a top-view of a machine embodying the invention, Fig. 2 is a vertical section on line 2—2 of Fig. 1, Fig. 3 is a vertical section on line 3—3 of Fig. 2, Fig. 4 is a horizontal section on line 4—4 of Fig. 2, on a larger scale, Fig. 5 is a vertical section on line 5—5 of Fig. 3, on a larger scale, and Fig. 6 45 is a vertical section on line 6—6 of Fig. 4, also on a larger scale.

Similar reference numerals indicate corresponding parts in all the figures.

On the bed 10 of the machine is located

the curling-shoe 11, and adjacent the same 50 at the entering side of the shoe are the feeding-finger 12 and the brim-guide 13, and removed therefrom the crown-guide or button 28, and below the shoe the heating-burner 29, all these parts being well known 55 in hat-brim curling machines.

Below the bed is supported a depending bracket 14, carrying a horizontal roller 15. Also below the bed 10 and inclosing said bracket and roller, is a receptacle 16 for the 60 water or other liquid used for wetting the brims of the hats prior to curling. For supporting the receptacle 16, two angular spring-clips 17 are attached to the bed 10, and engage lugs 18 on the receptacle, as 65 shown in Fig. 2. By pressing the clips inward by hand they are released from the lugs, thereby permitting the easy removal and replacement of the receptacle. A dampening-belt 19, made of loose cotton fabric 70 or wicking, or any other material suitable for transferring liquid from the receptacle to the hat-brim, passes around said roller 15 in the liquid 20 in the receptacle, and upward through an opening 21 in the bed 10 75 and thence continues upward and over a driving-roller 22. The main-face 25 of the brim-guide extends at its forward portion 59 to the hook 26 of the same, and said forward portion 59 is spaced from the body 27 80 of the brim-guide, forming an opening 23 in which the wet-belt passes upward. The forward extension 59 of the brim-guide protects the lower portion of the hat-brim from contact with the wet-belt, but its upper edge 85

is lower than the upper edge of the main part of the guide, and sufficiently low to expose the upper part of the brim to contact with the wet-belt over the full width of the wet-belt and for a vertical distance of approximately one-quarter of an inch, this being a proper distance for the required wetting. The belt is located close to the body-portion 27 of the brim-guide and by the same is kept in close contact with the 90 brim, during the passage of the brim in the guide. After passing over the roll 22 the belt passes down at the back of the brim- 95

guide to the receptacle. By means of the wet-belt, the brim of the hat is automatically properly damped for the curling operation of the hammer, so that the hand-dampening of the brim which was heretofore necessary and which was usually performed with a sponge before placing the hat in the machine, is done away with. The brim-guide is adjustable by swinging the same around its securing-bolt 86 by which it is fixed in place on the bed 10, and vertically by adjusting the thumbscrew 87 against the ear 88 which is kept normally raised by the spring-tension of the rear portion 89 of the guide.

After leaving the brim-guide, the brim passes between the feed-roller 30 and the feeding-finger 12, and enters the shoe, wherein it is acted upon by the hammer 50. Said hammer is provided with the usual hooked forward end or nose entering the curved groove of the shoe and acting to hammer the hat-brim 9 therein, whereby the brim is permanently curled. At its rear portion the hammer is provided with upwardly-projecting lugs 51, two at each side, between which is received a spring-arm 52 which is bolted at 53 to the hammer and supports the same. The arm 52 extends rearwardly from the hammer and is downturned and bent forward, as shown clearly in Fig. 3, and at its lower portion is bolted at 54 to a slide or carriage 55 which is longitudinally guided in two transverse keepers 56 of a carriage-bed 57 which is secured to the bed 10 of the machine. Reciprocating motion is given to the hammer by means of a connecting-rod 60 made of spring-metal and bolted at its forward end at 61 to the carriage 55 and pivoted at its rear end to a wrist-pin or stud 62 eccentric on a head 39 at the end of the driving-shaft 64 of the machine. It will be observed that there are no pivots or other loose joints whatever between the carriage and the nose of the hammer, hence there is no opportunity for play in any such joints, which was a serious objection in former machines, while at the same time the necessary yielding of the hammer in vertical direction required to cause the same at each blow to adapt itself to the particular conditions of the material between the hammer and shoe, is preserved. The strength of the spring 52 is such not only as to hold the hammer supported against the force of gravity in the position shown in Fig. 3, but so much more than this, that a slight lifting of the hammer out of true position meets with immediate resistance from the spring-arm 52. In this respect the mounting of this hammer differs from those counterbalanced or spring-balanced hammers heretofore employed in which there was no resistance to upward movement of the hammer. Such hammers

had unnecessary and disadvantageous upward play, resulting in imperfect curling, and undue wear on the overhanging upper edge of the shoe, which are overcome by the new means of mounting the hammer heretofore described. The hammer is vibratory supported by the spring, and the axis or point about which the vertical movement takes place, is located outside of the hammer itself, namely, within the spring, or at the point where the spring is fastened. A further source of difficulty with hammers heretofore in use lay in the means employed for giving them reciprocating movement, namely a connecting-rod having two pivot joints, one at the carriage and the other at the wrist-pin on the driving-shaft. By employing a spring-metal connecting-rod as described, which is flexible in the direction of rotation of the wrist-pin, the connecting-rod may be rigidly secured to the carriage. The other end of the connecting-rod 60 is turned as an eye 63 around the wrist-pin 62. When, due to wear or any other cause, play occurs at this point, the same may be taken up readily by contracting the eye by a blow with a hammer or other suitable tool. There is thus no play existing in the longitudinal movement of the curling-hammer, and the blows of the same are delivered firmly, uniformly and effectively. In order that the proper adjustment of the position of the hammer may be made, so that the full benefit of the exact movements of the same are obtained, the spring-arm 52 is provided with longitudinal slots 66 receiving the bolts 53 which are threaded in the hammer, so that the hammer may be located at any point relatively to the spring-arm necessary to bring the nose of the hammer into the exact desired relationship with the shoe. The shoe also is adjustable both longitudinally and laterally, by means of longitudinal recesses 67 in the rearwardly-projecting ears 68 of the shoe, said recesses being of greater width than the diameter of the attaching-bolts 69 and thereby permitting lateral adjustment of the shoe to the extent of the width of the slots. The carriage-bed 57 is provided with oppositely-arranged laterally extending lugs or ears 70, 71, each having a recess 72. Said lugs are preferably cast integral with the carriage-bed. They rest upon the bed 10, and support the carriage-bed 57 in a recess 49 of the same. Bolts 73 of less diameter than the width of the recesses 72, clamp the lugs 70 and 71 to the bed. The recesses 72 permit longitudinal adjustment of the position of the carriage-bed to the extent of the difference between the width of the recesses 72 and the diameter of the bolts 73, and thus afford an adjustment of the keepers 56 relatively to the carriage 55.

The feeding-finger comprises a strip 12 of

spring-metal which is mounted on a rest 41 which is slotted at its rear portion at 42 and secured to the bed 10 by a bolt 43 passing through the slot. The rest is thus adjustable longitudinally to the extent of the length of the slot, and angularly about the bolt, so as to place the finger in proper relation to the feed-roller 30. A thumb-screw 47 arranged horizontally in the forward portion of the rest 41 bears laterally against the feeding-finger at a point some distance back from the feed-roller, so that the spring-tension of the feeding finger toward the roller may be adjusted and the required pressure of the same obtained for reliably feeding the brim. In former machines the feeding finger was secured directly to the rest by screws passing therethrough. Such means of securing the finger to the rest did not afford the necessary range of adjustment of the finger, and did not permit its prompt adjustment or removal or replacement. These ends are now attained by providing a longitudinal clamping-plate 44, which is secured to the rest by screws 45, said plate having at its lower edge an inwardly-projecting flange 46 of the same width as the thickness of the finger 12. The finger 12 is clamped by the screws between the clamping-plate 44 and the rest, and is there held by friction in the desired position, the screws serving as a means for determining the horizontal position of the same, as shown in Fig. 6. For adjusting the finger, or releasing the same, it is only necessary to release the screws 45 by a backward turn of the same, whereby the clamping-plate is released from the finger and the latter may be freely moved. The freedom of adjustment of the finger, and its readiness of removal, are of great advantage in securing the reliable feed of the hat brims and quickly changing the machine from feeding one style or shape of brim to another.

The feed-roller 30 is mounted at the lower end of a vertical shaft 31 supported in a standard 32 which rises from and forms a part of the rest 41. At its upper end the shaft carries a bevel-gear 33, with which meshes a pinion 34 which is secured to a horizontal shaft 35, the latter being supported in side-standards 36, 37, which are bolted to the bed 10. From the standard 37 extends laterally a bracket 70, which supports a shaft 71 on the inner end of which is carried the driving-roller 22 of the dampening-belt. A belt-and-pulley transmission 72, 73, 74 from the countershaft 35 imparts motion to the roller-shaft 71. The counter-shaft 35 is driven from the driving-shaft 64 by a belt-and-pulley transmission comprising a small pulley 77 on the driving-shaft 64, a larger pulley 78 on a sleeve 79 mounted loosely on a stud or short-shaft 99 secured to the standard 36, a small pulley 80 secured to said sleeve, a larger pulley 81 on the countershaft 35, and belts 82, 83, passing over said pulleys 77, 78, and 80, 81, respectively. The speed of rotation of the countershaft 35 is thereby largely reduced from that of the driving-shaft, as is required for rotating the feed-roller at the necessary slow speed for proper feeding of the hat-brim.

For adjusting the position of the countershaft longitudinally of the machine, so that the position of the same may be at all times exactly over the center of the bevel-gear 33, so as to secure the proper meshing of said gear and the pinion 34, the recesses 90 in the feet of the standards 36, 37, respectively, are made wider than the diameter of the securing bolts 91 which secure the standards to the bed 10. Thereby a longitudinal adjustment of the position of the standards on the bed, to the extent of the difference between the width of the slots and the diameter of the bolts, is provided, whereby the countershaft 35 may be accurately positioned in accordance with changes of position of the feed-roller which may be made. A corresponding adjustment of the position of the wet-belt 19 is secured by providing horizontal slots 93 in the bracket 70 for the screws 94 by which the same is secured to the standard 37. By this means the position of the dampening-belt may be varied and the same brought into proper position relatively to the brim-guide when the latter is adjusted or readjusted, so as to properly coat for dampening the brims fed in the new position.

The driving-shaft 64 is supported in a bracket 98 at the rear-portion of the bed, or may be supported in any other suitable manner. Tight and loose pulleys 95, 96, and an overhead driving-belt 97 provide for transmitting motion thereto and stopping and starting the machine whenever desired.

For preventing slip of the wet-belt on the driving roller 22 and lower roller 15, these rollers may be roughened or provided with projecting pins 58, as shown in Fig. 2, so that the belt is positively driven.

The machine described provides a rapid and effective means for curling hat-brims in an entirely automatic manner, the only manual operation required being the proper feeding of the hats to and through the machine.

It is obvious that the invention is not limited to the details of construction shown and described, and that the same may be changed without departing from the spirit of the invention as set forth in the claims.

I claim:

1. A hat-brim curling machine, comprising curling-devices, and a moving dampen-

- ing device for dampening the brim before the entrance of the same between said curling devices.
2. A hat-brim curling machine, comprising curling-devices, a brim-guide, and a moving brim-dampening device adjacent the path of the brim between said brim-guide and curling-devices.
3. A hat-brim curling machine, comprising curling-devices, a brim-guide, feeding-devices, and a moving brim-dampening device adjacent the path of the brim between said brim-guide and the feeding-devices.
4. A hat-brim curling machine, comprising curling-devices, a continuously-moving feeding-device in advance thereof, and a continuously-moving dampening device in advance thereof.
5. A hat-brim curling machine, comprising curling-devices, and a wet-belt movable in contact with the brim being fed thereto.
6. A hat-brim curling machine, comprising curling-devices, and a wet-belt movable transversely of the brim being fed thereto, in contact therewith.
7. A hat-brim curling machine, comprising curling-devices, a brim-guide, a dampening-device, and means for pressing said dampening-device against the brim passing said guide.
8. A hat-brim curling machine, comprising curling-devices, a dampening-device adjacent the path of the brim being fed thereto, and means for adjusting said dampening-device transversely of said path.
9. A hat-brim curling machine, comprising curling-devices, a dampening-device adjacent the path of the brim being fed thereto, means for adjusting said dampening-device transversely of said path, and means for adjusting said dampening-device longitudinally thereof.
10. A hat-brim curling machine, comprising curling-devices, brim-feeding devices, a brim-dampening device, means for adjusting the position of the curling-devices, means for adjusting the position of the brim-feeding-devices, and means for adjusting the position of the brim-dampening device.
11. A hat-brim curling machine, comprising a horizontal curling-shoe and a curling-hammer coöperating therewith and means supporting the hammer to vibrate vertically relatively to the shoe, the axis of vibration of the hammer being outside of the same.
12. A hat-brim curling machine, comprising a horizontal curling-shoe, a curling-hammer coöperating therewith, and a spring supporting said hammer so as to vibrate vertically relatively to the shoe, the axis of vibration of the hammer being outside of the same and within the length of the spring.
13. A hat-brim curling machine, comprising a curling-shoe, and a curling-hammer engaging the same and spring-actuated against vertical upward movement.
14. A hat-brim curling machine, comprising a curling-shoe, and a curling-hammer engaging the same and spring-actuated against vertical upward and against vertical downward movement.
15. A hat-brim curling machine, comprising a curling-shoe, a curling-hammer, a spring-arm rigidly connected to the hammer, and means rigidly supporting said spring-arm against vertical movement either upward or downward, at a point removed from the hammer.
16. A hat-brim curling machine, comprising a curling-shoe, a hammer engaging the same, a carriage for the hammer, a driving-shaft, and a spring-metal connecting rod secured rigidly to the carriage and connected eccentrically to the driving-shaft.
17. A hat-brim curling-machine, comprising a curling-shoe, a curling-hammer, a spring-arm for supporting the hammer, and means for adjusting the hammer on the arm.
18. A hat-brim curling-machine, comprising a curling-shoe, a curling-hammer engaging the same, a feeding-roller adjacent said curling-shoe and hammer, a vertical shaft supporting said feeding-roller, a gear-wheel on said shaft, means for adjusting said feeding-roller horizontally relatively to said shoe and hammer, a horizontal countershaft, a pinion on the countershaft engaging said gear-wheel, and means for adjusting said countershaft and pinion horizontally relatively to said vertical shaft and gear-wheel.
19. A hat-brim curling machine, comprising a curling-shoe, a curling-hammer engaging the same, a feeding-roller adjacent said curling-shoe and hammer, a vertical shaft supporting said feeding-roller, a gear-wheel on said shaft, a countershaft, standards, one at each side of the machine adjustable longitudinally and laterally and supporting said countershaft, a pinion on the countershaft engaging the gear-wheel, a wet-belt supported in advance of the feeding-roller, means on one of said standards for carrying said belt at its upper portion, and means for adjusting said carrying means.
20. A hat-brim curling machine, comprising a curling-shoe, a curling-hammer engaging the same, a feeding-roller, a countershaft, means connecting the countershaft with the feeding-roller for driving the latter, a wet-belt, and means connected with the countershaft for driving the wet-belt.
21. A hat-brim curling machine, comprising a curling-shoe, a curling-hammer engaging the same, a feeding-roller, a countershaft, a pinion-and-gear transmission between the countershaft and the feeding-

roller, a wet-belt, and a belt-and-pulley transmission between the countershaft and the wet-belt.

22. In a hat-brim curling-machine, a rest, 5 a spring-metal feeding-finger, a clamping-plate having a flange at its lower portion of the same width as the thickness of the feeding-finger, and screws threaded in the rest and clamping the feeding-finger between 10 the same and the upper portion of the clamp-

ing-plate, said screws determining the position of the lower edge of the feeding-finger.

In testimony that I claim the foregoing as my invention, I have signed my name in presence of two subscribing witnesses.

GUSTAV SEGSCHNEIDER.
